CHAIR

John M. Dorton, Oak and Nettleton Sts.,
Bonner Springs, Kans.
Filed Dec. 1, 1958, Ser. No. 777,255
2 Claims. (Cl. 155—162)

This invention relates to new and useful improvements in chairs, and has particular reference to certain features contributing to the comfort and adjustability of chairs.

A principal object of the present invention is the provision of a chair having novel structure whereby the back cushion thereof may be tiltably adjusted to any position from substantially upright to substantially horizontal, whereby the height of the back cushion may be adjusted, and whereby the stiffness or yieldability of the back cushion may be adjusted, all as may be required by the individual preference of each user.

Another important object is the provision of a chair of the character described, wherein the back cushion is so related to the seat cushion that the former moves up and down with the latter as the latter is compressed by the weight of the occupant. This is particularly important in automotive seating, since relative movement between the seat and back cushions due to jostling and bouncing during travel, in seats wherein the seat and back cushions are supported independently, results in friction against the rider's back and flexure of his spine, with resultant discomfort and fatigue.

Still another object is the provision of a chair of the character described which is well adapted for use in virtually all types of furniture, automotive and transportation seating.

Other objects are simplicity and economy of construction, efficiency and dependability of operation, and ease and convenience of manipulation.

With these objects in view, as well as other objects which will appear in the course of the specification, reference will be had to the drawing, wherein:

FIG. 1 is a side elevational view of a chair embodying the present invention,

FIG. 2 is a fragmentary sectional view taken on line II—II of FIG. 1,

FIG. 3 is an enlarged, foreshortened fragmentary sectional view taken on line III—III of FIG. 1,

FIG. 4 is a fragmentary sectional view taken on line IV—IV of FIG. 3, and

FIG. 5 is a sectional view taken on line V—V of FIG. 4.

Like reference numerals apply to similar parts throughout the several views, and the numeral 2 applies generally to the seat frame of the chair, said seat frame including a pair of tubular members 4 extending from front to rear respectively at opposite sides of the chair, a front leg 6 and a rear leg 8 affixed respectively to the forward and rearward ends of each member 4 and depending therefrom, and a seat cushion supporting platform 10 extending between and rigidly affixed to members 4 and forming a portion of the seat frame. Affixed to platform 10 is a seat cushion 12 which is resiliently compressible. The specific internal construction of said cushion is not pertinent to the present invention. Tubular members 4 are open at their rearward ends.

A back frame indicated generally by the numeral 14 includes a pair of tubular slides 16 inserted slidably into the rearward end portions of members 4 and extending rearwardly therefrom. Said slides are movable forwardly and rearwardly in members 4, and each slide is fixable at any desired position by means of a set screw 18 threaded in the associated member 4.

A tubular upright 20 is welded or otherwise fixed adjacent its lower end to the rearward end of each slide 16,

2

and extends upwardly approximately to the level of the upper surface of seat cushion. Pivotable to the upper end of each of said uprights, as by pivot pin 22, is a segmentally shaped plate 24 disposed concentrically with pivot pin 22. Pivot pins 22 are coaxial, and plates 24 lie in parallel planes, each being movable through a slot 26 formed longitudinally in the associated upright 20. Each of plates 24 has a series of angularly spaced apart notches 28 formed in the arcuate edge thereof. A latch pin 30 is disposed axially within the lower portion of each of uprights 20, and is provided at its upper end with a tooth 32 adapted to engage selectively in any of notches 28 of the associated plate 24. Said latch pin is urged upwardly to engage said plate by a coil spring 34 disposed therebeneath in upright 20 and based on a plug 36 threaded in the lower end of said upright.

A pin 38 is threaded into each of latch pins 30, and projects transversely therefrom through a slot 40 formed longitudinally in the associated upright 20. A tubular cross bar 42 extends horizontally and transversely between slides 16, and is welded or otherwise fixed at the juncture between slide 16 and upright 20, at each side of the chair. A shaft 44 extends axially through said cross bar, and may be oscillated about its axis. At the left side of the chair, a crank 46 is affixed to one end of shaft 44 by nut 48, and pivotally connected to the pin 38 at that side of the chair by nut 50. At the right side of the chair, a crank 52 is affixed to the opposite end of shaft 44 by nut 54, and pivoted to pin 38 at that side of the chair by nut 56. Crank 52 is provided with a forward extention terminating in a finger ring 58.

Welded or otherwise fixed to each segmental plate 24, so as to be pivotal therewith relative to upright 20 about pivot 22, is a tubular member 60 which normally projects upwardly from pivot 22. Associated with each of members 60 is an upward extension 62, the lower end portion 63 thereof being of reduced diameter, being engaged slidably in member 60 and fixable therein by means of a set screw 64. The upper end portions of extensions 62 are curved rearwardly, and are rigidly connected together by a horizontal cross bar 66. A back cushion 68 which is thin and resilient as shown is connected along its lower edge to the upper rearward edge of seat cushion 12 by a suitable hinge 70. The upper end portion of said back cushion is curved rearwardly and downwardly, and is attached to cross bar 66 by any suitable means such as rivets 72. The specific internal construction of the back cushion is not pertinent to the present invention, and may consist of any suitable arrangement of spring wires, meshes or strips, overlaid by layers of padding and covering. It will be understood that whenever seat cushion 12 is compressed by the weight of a person sitting thereon, the lower edge of the back cushion will also be pulled downwardly, the back cushion being rendered vertically movable by the resiliently yieldable curved portion thereof.

The operation of the chair is believed to be reasonably apparent from the foregoing description of its construction. When the occupant of the chair desires to vary the angle of reclining of back cushion 68, he pulls upwardly on finger ring 58, which operates through shaft 44 and cranks 46 and 52 to slide latch pins 30 downwardly in uprights 20 against the pressure of springs 34, thereby releasing latch teeth 32 from notches 28 of latch plates 24. This permits members 60 and extensions 62 to be pivoted forwardly or rearwardly about pivots 22, which of course also pivots back cushion 68 about hinge 70. When said back cushion is at the desired angle, the occupant releases ring 58, whereupon springs 34 urge latch pins 30 upwardly to engage teeth 32 thereof in whatever notches 28 of the latch plates then register with said teeth. In this manner, the back cushion may be lowered to substantially a horizontal position, so that the seat and back cushions may

serve as a full reclining couch if desired. In this usage, the chair legs 6 and 8 should be secured to the floor so as to maintain the chair upright against the overbalanced load.

The adjustment of the reclining angle provided by pivots 22 is of course by steps only, since notches 28 are disposed at spaced apart intervals. Fine adjustments of the reclining angle, when desired, may be obtained by loosening set screws 18 and moving slides 16 forwardly or rearwardly in seat frame members 4. Since this moves the entire back frame 14 forwardly or rearwardly, including cross bar 66 to which the back cushion is affixed, the angle of the back cushion is adjusted thereby.

Since the pivots 22 and hinge 70 are offset, adjustment of the back by tilting the back frame on pivots 22 causes the upper end of the back cushion, at cross bar 66, to be moved toward or from hinge 22 and thereby changes the tension in which said back cushion is held between its two points of attachment. If the back is tilted forwardly about pivots 22, bar 66 moves closer to hinge 70, and the tension of the back cushion is lessened. If the back is tilted rearwardly, bar 66 moves farther away from hinge 70 and the tension of the back cushion is increased. The tension of the back cushion determines its "feel" or sensation of "softness" or "depth," and is therefore quite an important feature in the comfort of the chair. The tension of the back cushion may be adjusted by loosening set screws 64 and raising or lowering extensions 62 with respect to members 60, at any setting of pivots 22. Moreover, adjustment of the back cushion tension by this means may also alter the reclining angle of the back, as the radius of the curved portion of the back is increased or decreased by changes of tension therein. This change of angle may be compensated by loosening set screws 18 and adjusting slides 16. This, for any setting of pivots 22, the precise angle of recline and degree of tension of the back cushion desired may be provided by properly relating the adjustments permitted by set screws 18 and 64.

While I have shown and described a specific embodiment of my invention, it will be readily apparent that many minor modifications of structure and operation could be made without departing from the spirit of the invention as defined by the scope of the appended claims.

What I claim as new and desire to protect by Letters Patent is:

1. A chair comprising a seat frame, a back frame

carried by said seat frame and extending upwardly from the rearward portion thereof, a resiliently compressible seat cushion carried by said seat frame, and a resilient back cushion hinged along its lower edge to the upper rear edge of said seat cushion and extending upwardly therefrom, the upper edge portion of said back cushion being curved rearwardly and downwardly and being secured to the upper end of said back frame, said back frame consisting of upper and lower sections pivotally joined together on an axis parallel to the hinged connection of said back cushion to said seat cushion, whereby the upper portion of said back frame may be tilted forwardly or rearwardly to adjust the angle of inclination of said back cushion, and latch means operable to secure said upper back frame section selectively at any of a series of angles of inclination, the lower section of said back frame being adjustably movable forwardly and rearwardly with respect to said seat frame, and the upper section of said back frame being adjustably extendible to vary the distance between the upper end thereof and the axis of its pivotal connection to the lower back frame section.

2. The structure as recited in claim 1 wherein said latch means comprises a segmental latch plate fixed to the upper section of said back frame concentrically with the pivotal connection between said upper and lower sections, and having a series of notches formed in the arcuate edge thereof, a latch pin carried by the lower section of said back frame for movement toward and from engagement with any one of said latch plate notches, resilient means urging said latch pin toward its notch-engaging position, and manually operable means for moving said latch pin away from its notch-engaging position.
